CONTAINER

Reynolds Guyer, St. Paul, Minn., assignor to
 Waldorf Paper Products Company, St. Paul,
 Minn., a corporation of Minnesota

Application July 18, 1942, Serial No. 451,399

6 Claims. (Cl. 229—14)

My invention relates to containers and has for an object to provide a container particularly adapted to be used for containing liquid products intended to be solidified in the container by freezing.

An object of the invention resides in providing a container having an outer shell and a liner therein and in constructing the liner to be leak-proof.

Another object of the invention resides in constructing the container so as to withstand the stresses arising therein due to the weight of the liquid within the container.

A feature of the invention resides in providing the liner with flanges overlying the upper ends of the lateral walls of the shell and disposed upon the exterior of the container.

Another object of the invention resides in providing a top for the container having flanges along the edges thereof overlying the flanges of the liner, and of a width less than the width of the flanges of the liner to expose the lower marginal portions thereof.

A still further object of the invention resides in providing a band adhesively secured to the flanges of the liner and the flanges of the top and also to the portion of the lateral walls of the shell adjacent the marginal portions of the flanges of the liner.

A feature of the invention resides in constructing the flanges of the top with marginal portions extending beyond the flanges of the liner and in adhesively attaching said marginal portions of the flanges of the top to the walls of the shell.

Another object of the invention resides in constructing the liner with folded-over corner portions and in constructing certain of the walls of the shell with corner flaps and in arranging said folded-over corner portions of the liner and the flaps of said shell between the walls of the liner and the shell and in holding said parts in position therebetween by means of flaps of the liner.

An object of the invention resides in providing in the top a flap hingedly connected thereto by means of a diagonal score.

A feature of the invention resides in providing said flap with flanges adapted to overlie the flanges of the liner and in providing means for adhesively attaching said flanges in position relative to the lateral walls of the shell.

Other objects of the invention reside in the novel combination and arrangement of parts and in the details of construction hereinafter illustrated and/or described.

In the drawings:

Fig. 1 is a perspective view of a container illustrating an embodiment of my invention.

Fig. 2 is a developed view of the blank from which the shell of the invention is constructed.

Fig. 3 is a developed view of the blank from which the liner of the container is constructed.

Fig. 4 is a developed view of the blank from which the top of the container is constructed.

Fig. 5 is a developed view of the blank from which the cover for the container is constructed.

Fig. 6 is a perspective view showing the manner of assembling the shell of the container.

Fig. 7 is a perspective view illustrating the manner of assembling the liner within the shell.

Fig. 8 is a perspective view showing the container with the top applied thereto and partly secured in place.

Fig. 9 is a perspective view of the assembled container with the closure in opening position illustrating the method of filling the container.

Fig. 10 is a sectional view taken on line 10—10 of Fig. 9 and drawn to a greater scale.

Fig. 11 is a perspective view similar to Fig. 9 of a modification of the invention.

Fig. 12 is a view similar to Fig. 10 and taken on line 12—12 of Fig. 11.

My invention comprises a shell 16 having a liner 17 disposed within the same which forms a container open at the top and indicated in its entirety by the reference numeral 15. The container 15 is closed by means of a top 18 and has a cover 19 overlying said top. These parts will now be described in detail.

The shell 16 is constructed from a blank shown in Fig. 2 which is provided with two longitudinal scores 21 and 22 and with two transverse scores 23 and 24 which divide the blank into a bottom 25, lateral walls 26, 27, 28 and 29 and corner flaps 31. The flaps 31 are separated from the walls 26 and 27 by means of cuts 32 which extend in continuation of the scores 21 and 22 and are disposed between the scores 23 and 24 and the edges of the blank. The blank from which the shell 16 is constructed is folded along the various scores to bring the walls thereof in erect position and the flaps 31 within the interior of the shell and adjacent the walls 26 and 27.

For the purpose of erecting the container, a form is used which is indicated in its entirety by the reference numeral 33 and which is best shown in Fig. 6. This form may be constructed of wood and has a bottom 34 and side and end walls 35 and 36 connected thereto. These walls are so spaced as to snugly receive the carton when in erected position, whereby the walls and flaps of

the carton are held in proper position, as clearly shown in Fig. 7.

The blank from which the liner 17 is constructed is shown in Fig. 3 and is preferably constructed of a water-proof paper. This blank is provided with longitudinal scores 37 and 38 and with transverse scores 39 and 41 which divide the blank into a bottom 42 and lateral walls 43, 44, 45 and 46, and with corner portions 47 disposed between the lateral walls and connected thereto. The blank has extensions 48 and 49 which project outwardly from the lateral walls and beyond the corner portions to form flanges. The blank is scored along lines 51 which separate the flanges 48 from the walls 45 and 46. The blank is further formed with double scores 52 which separate the flanges 49 from the walls 43 and 44. In the corner portions 47 of the blank are provided scores 54 which divide said corner portions into foldable corner parts 55 and 56.

In the erection of the liner 17, the walls thereof are folded inwardly along the scores 37, 38, 39 and 41, the corner portions are doubled back upon themselves along the scores 54 and the folded parts 55 and 56 folded back upon the walls 43 and 44, as best shown in Fig. 7. The folded structure is then inserted into the shell 16, as indicated in Fig. 7 with the corner portions 47 and with the flaps 31 of the shell 16 disposed between the walls 43 and 44 of the liner 17 and the walls 26 and 27 of the shell 16. The liner is then moved downwardly until the bottom 42 thereof rests upon the bottom 25 of the shell 16. The parts are so proportioned that the liner fits snugly within the shell and so that the flanges 48 and 49 thereof may be folded outwardly upon the exterior of the shell.

The top 18 of the container is constructed from a blank shown in detail in Fig. 4. This blank is provided with longitudinal scores 57 and 58 and with transverse scores 59 and 61 which divide the blank into a top proper 62 and flanges 63 and 64 extending outwardly therefrom. The corners of this blank are entirely removed so that the ends of said flanges lie adjacent one another when the top is folded into erected position. The flanges 64 of the top 18 have cuts 65 therein which extend from the edges of said flanges and up to the scores 58 and 59. The blank further has a diagonal score 66 which extends from the ends of the cuts 65 diagonally across the top proper 62. By means of this construction, a flap 67 is provided which may be swung upwardly along the score 66 to form an inlet into the container or into a position in which the same serves as a closure for the inlet. Severance of the flanges 64 along the cuts 65 form on the closure 67 flanges 68 which lie in continuation with the flanges 64 when the closure is in closing position.

In assembling the top 18, the top proper is placed upon the upper end of the container 15 and the flanges 63 and 64 thereof folded into a position overlying the flanges 48 and 49 of the liner 17. Likewise, the flanges 68 of the closure 67 are caused to overlie the flanges 48 and 49 of the liner 17. The top 18 and the closure 67 are temporarily held in position upon the container 15 by means of a number of spring clips 70 and 71 hingedly connected to the walls 35 and 36 of the form 33 by means of screws 72. These clips have fingers 73 which overlie the top 18 and hold the same in place. When the clips 71 are not desired for use, the same may be sprung into the positions shown in Fig. 6. When the same are

used to hold the top 18 in place, the clips are arranged as shown in Fig. 8.

It will be noted that the flanges 63, 64 and 68 are shorter than the flanges 48 and 49, as best shown in Fig. 8. This leaves the marginal portions 75 of the flanges 48 and 49 exposed below the outermost edges of the flanges 63, 64 and 68. The top 18 is attached to the shell 16 by means of two strips of adhesive tape designated by the reference numerals 76 and 77. The strip of adhesive tape 76 is first applied to the flange 64 adjacent one of the cuts 65 and wrapped about the portion of the flange 68 issuing from wall 44, the flange 64 issuing from the top 18 and the portion of the wall 27 lying adjacent the flange 49. This strip of adhesive tape is next wrapped about the corresponding parts along the wall 28 of the shell 16 and then partly about the corresponding parts along the wall 26. Clip 70 is now disengaged and the strip of adhesive tape 77 is now applied to the parts overlying the walls 28, 26 and 27 in the same manner as the strip 76. It will be noted that the strips of adhesive 76 and 77 are of sufficient width to cover the flanges 63, 64 and 68, the marginal portions 75 of the flanges 48 and 49 and to extend well down upon the lateral walls of the shell 16.

Upon removal of the two clips 71, the closed container may be removed from the form 33, whereupon the container is ready for filling. In the filling of the container, the flap or closure 67 is folded back as shown in Fig. 9 and the contents to be filled are discharged into the same through a spout or faucet such as indicated at 79. After the container has been filled, the closure 67 is closed and the flanges 68 thereon caused to overlie the flanges 48 and 49 of the liner 17. The same are then secured in position by a strip of adhesive tape similar to the strips 76 and 77 and in the same manner as employed in the application of the strips 76 and 77. This strip has, however, not been shown in the drawings, though it can be readily comprehended that the strip and method of procedure is exactly the same as that employed in securing the top 18 to the container 15.

For the purpose of protecting the top 18, the cover 19 is employed. This cover is constructed from a blank shown in detail in Fig. 5. This blank has two longitudinal scores 81 and 82 and two transverse scores 83 and 84 which divide the blank into a top 85 and lateral walls 86 and 87. The blank from which the cover 19 is constructed is formed with cuts 88 which lie in continuation of the scores 83 and 84 which extend from the scores 81 and 82 to the edges of the blank. These cuts form flaps 89 at the corners of the blank which are adapted to be secured to the adjacent walls 87 by any suitable adhesive. The flaps 89 are preferably secured to the walls 87 at the factory, so that assembly of the same at the location of use becomes unnecessary. In order to minimize the space taken by these covers, the walls 86 thereof are formed with diagonal scores 81 which permit of collapsing the covers into compact flat form. In Fig. 1, the container is shown as having the cover applied thereto. It will be noted that the walls of the cover are sufficiently wide to cover the sealing strips 76 and 77.

In Figs. 11 and 12, I have shown a modification of the invention. Inasmuch as the construction of the container shown in these figures is similar to that previously described, the description thereof will not be repeated and the same refer-

ence numerals, to which the digit "1" has been applied, will be used to designate the corresponding parts. In this form of the invention, the flanges 148 and 149 of the liner 117 are made shorter than the flanges 163, 164 and 168, so that marginal portions 115 are left on the flanges of the top 118, which marginal portions project below the flanges of the liner. On the marginal portions of all of the flanges of the top is applied an adhesive, such as designated at 170 in Figs. 11 and 12. This adhesive may be of the type which becomes tacky upon the application of moisture thereto or it may be the type which becomes tacky upon heating. In either event, the adhesive is used to attach the closure to the shell of the container and takes the place of the strips of adhesive tape used with the other form of the invention.

The advantages of my invention are manifest. A container constructed in accordance with my invention may be formed of inexpensive paper construction and has sufficient strength to withstand the pressure produced by the weight of the liquid within the same. With my invention, a water-tight container is provided which does not rely on glued joints for tightness. With my invention, all of the folded parts and corner flaps are disposed between the walls of the liner and shell and thus become completely concealed. The closure used with my container provides ample access for filling and does not increase the cost of the container. When the closure is applied, the container is as strong as if it had no closure. My improved container can be constructed at a nominal expense and is highly practical and serviceable.

Changes in the specific form of my invention, as herein described, may be made within the scope of what is claimed without departing from the spirit of my invention.

Having described my invention, what I claim as new and desire to protect by Letters Patent is:

1. A container comprising a shell provided with a bottom and lateral walls connected thereto and extending upwardly therefrom to terminate along raw upper edges, a liner within said shell having a bottom and lateral walls overlying the bottom and lateral walls of the shell and diagonally creased folded corner parts connecting adjacent lateral walls, flanges formed on the upper ends of the lateral walls of the liner and folded over said raw edges and back upon and overlying the upper areas of the lateral walls of the shell upon the exterior of the shell, a top for the upper end of the container, flanges on said top extending downwardly therefrom and overlying the flanges of the liner and means for holding all of said flanges in position relative to the lateral walls of the shell.

2. A container comprising a shell provided with a bottom and lateral walls connected thereto and extending upwardly therefrom, a liner within said shell having a bottom and lateral walls of the shell, flanges formed on the upper ends of the lateral walls of the liner and folded back upon and overlying the upper edges of the lateral walls of the shell upon the exterior of the shell, a top for the upper end of the container, flanges on said top extending downwardly therefrom and overlying the flanges of the liner, the flanges of the top terminating short of the flanges of the liner to expose the lowermost marginal portions thereof and a band overlying the flanges of the top, the lower marginal portions of the flanges of the liner and the

portions of the lateral walls of the shell adjoining the flanges of the liner, said band being adhesively attached to the parts which it overlies.

3. A container comprising a shell provided with a bottom and lateral walls connected thereto and extending upwardly therefrom, a liner within said shell having a bottom and lateral walls overlying the bottom and lateral walls of the shell, flanges formed on the upper ends of the lateral walls of the liner and folded back upon and overlying the upper edges of the lateral walls of the shell upon the exterior of the shell, a top for the upper end of the container, flanges on said top extending downwardly therefrom and overlying the flanges of the liner, the flanges of the top having marginal portions extending below the flanges of the liner, said marginal portions having adhesive attached to the portions of the lateral walls adjoining the flanges of the liner.

4. A container comprising a shell provided with a bottom and lateral walls connected thereto and extending upwardly therefrom, a liner within said shell constructed from a blank having intersecting transverse and longitudinal scores dividing the blank into a bottom, lateral walls and corner portions all connected to one another, said blank being diagonally scored at the corner portions forming foldable corner parts, flanges issuing outwardly from the ends of the lateral walls, said blank being foldable to bring the lateral walls into erect position within the walls of the shell and with the bottom overlying the bottom of the shell and with the corner parts in folded-over position and disposed between opposite facing walls of the liner and corresponding walls of the shell, said flanges being folded over the upper ends of the lateral walls of the shell, a top for the upper end of the container and means for securing said top and the flanges of said liner in position relative to the lateral walls of the shell.

5. A container comprising a shell provided with a bottom and lateral walls connected thereto and extending upwardly therefrom, a liner within said shell constructed from a blank having intersecting transverse and longitudinal scores dividing the blank into a bottom, lateral walls and corner portions all connected to one another, said blank being diagonally scored at the corner portions forming foldable corner parts, flanges issuing outwardly from the ends of the lateral walls, said blank being foldable to bring the lateral walls into erect position with the walls of the shell and with the bottom overlying the bottom of the shell and with the corner parts in folded-over position and disposed between opposite facing walls of the liner and corresponding walls of the shell, said flanges being folded over the upper ends of the lateral walls of the shell and a top for the upper end of the shell, said top having flanges thereon folded outwardly therefrom and overlying the flanges of the liner and means for securing the flanges of the top and the liner in position relative to the lateral walls of the shell.

6. A container comprising a shell constructed from a blank having intersecting transverse and longitudinal scores dividing the blank into a bottom, lateral walls and corner flaps, said corner flaps being severed along one of the scores of said flaps and being foldable into position upon the interior of the shell adjacent the adjoining wall of the shell, a liner within said shell constructed from a blank having intersecting transverse and longitudinal scores dividing the liner blank into a bottom, lateral walls and corner portions all connected to one another, said liner blank

being diagonally scored at the corner portions forming foldable corner parts, flanges issuing outwardly from the ends of the lateral walls, said liner blank being foldable to bring the lateral walls into erect position within the walls of the shell and with the bottom overlying the bottom of the shell and with the corner parts in folded-over position and disposed between opposite fac-

ing walls of the liner and corresponding walls of the shell, said flanges being folded over the upper ends of the lateral walls of the shell, a top for the upper end of the container and means for securing said top and the flanges of said liner in position.

REYNOLDS GUYER.
